COMMUTATOR TRIMMING TOOL

Ervin Bowker, Fall River, Mass., assignor of one-third to Douglas J. Richardson, Fall River, Mass., and one-third to Major W. Wheelock, Tiverton, R. I.

Application April 27, 1940, Serial No. 332,096

5 Claims. (Cl. 82—4)

This invention relates to a tool for trimming or re-surfacing the commutator of an armature for an electric motor or generator; and has for one of its objects to provide a simple and inexpensive tool which may be used for the re-surfacing of the segment of a commutator and may also be used for cutting back the insulation between such segments.

Another object of this invention is to provide a tool which may be screw fed forward but which, when the forward feed has been completed, may be returned to starting position by a sliding action without the necessity of a reverse rotation comparable to the forward screw feeding of the device.

Another object of the invention is to provide a tool the use of which upon a commutator will suffice to perform the desired function in much less time than comparable tools which I know of whereby the result on the work may be materially speeded up.

Another object of the invention is to so mount the bit of the device that it may be accurately adjusted such as through a threaded arrangement of a micrometer type.

Another object of the invention is to provide an extremely simple construction of bit holder with inherent resiliency which may be drawn together on the bit and the same securely held.

Another object of the invention is to provide an arrangement whereby the adjustment of the bit will be in a straight line toward and from the center of rotation and at right angles to the center of rotation at all points in its movement so that the same cutting edge of the bit is presented regardless of the point in the range of its movement.

Another object of the invention is to provide a simple chuck with an arrangement whereby a true centralizing mounting of the fixed part of the device upon the armature shaft may be had with an arrangement for the accommodation of varying sizes of armature shafts.

With these and other objects in view, the invention consists of certain novel features of construction, as will be more fully described, and particularly pointed out in the appended claims.

In the accompanying drawings:

Fig. 1 is a top plan view, partly in section, illustrating my tool in full lines with the armature upon which the device is to operate in dotted line;

Fig. 2 is an end view of my tool showing the armature shaft in section and taken on substantially line 2—2 of Fig. 1 looking in the direction of the arrows;

Fig. 3 is an opposite end view of the device with the armature shaft removed;

Fig. 4 is a section on line 4—4 of Fig. 1;

Fig. 5 is a perspective view of the bit holder looking at one side thereof;

Fig. 6 is a perspective view of the bit holder looking at the other side thereof;

Fig. 7 is a perspective view of a carrier member through which various adjustments of the device may be readily made;

Fig. 8 is a sectional view of the member of Fig. 7 shown mounted in position and taken on line 8—8 of Fig. 1;

Fig. 9 is a sectional view of the cylindrical part of my device which is fixed to the armature shaft;

Fig. 10 is a section on substantially line 10—10 of Fig. 9, illustrating the armature shaft and split sleeve thereabout mounted in position in this barrel member;

Fig. 11 is a perspective view of the arm which is mounted upon the member shown in Fig. 7 which engages the thread shown in Fig. 9;

Fig. 12 is a side elevation of the device with the undercutting tool for removing the insulation between the armature segment shown as mounted in position;

Fig. 13 is a section on line 13—13 of Fig. 12;

Fig. 14 is a central sectional view of a modified form of the device.

It frequently occurs in electric generators or motors that the brushes which contact the commutator of the armature wear the commutator to such an extent that the commutator must be trimmed or re-cut in order that a smooth surface be provided. The tool to which this invention relates is a device which is mounted upon the armature shaft when such armature is held in a vice and by turning one of the parts of the device about the part which is clamped to the armature shaft, a cutting tool is fed helically forward to trim the armature. Usually it is necessary to retrace the rotary action of the cutting tool in order that the device may be restored to its original position for a second cut; and in order that such retracing of the feeding stroke may be eliminated I have arranged for a disengagement of the feed so that the parts may be returned to their original starting position by sliding. Further, it has been known in armature cutting tools that the bit which performs the cut is so mounted that it swings through an arc to and from the center about which the parts operate; and in order to improve upon this arrangement I have provided a mounting of the tool bit so that it moves in a plane at right angles to the center about which it turns and in a straight line toward and from such center. Thus, the same edge of the tool is presented to the work regardless of its point of adjustment.

After an armature commutator is turned down, it frequently occurs that the insulation between the segment is at the same level being turned down by the cutting of the tool; and it is necessary to "undercut" or cut away the insulation between the segments so that the brush which

contacts the commutator segments will not rub upon the insulation. Rather complicated arrangements are commonly provided for such undercutting, but by the use of the device which is herein described, it is merely necessary for me to remove the bit which does the cutting of the armature commutator and replace this bit with a rotary mounted tool in a carrier which fits into the same opening from which the bit was taken, and then by holding the part which previously rotated in the vice and disengaging the thread feed and the binding of the adjustment member so that the same may slide, I may slide the tool along the line parallel to the axis and by manually turning the same cut the insulation between the segments that the desired undercutting may be performed; and the following is a more detailed description of the present embodiment of this invention, illustrating the preferred means by which these advantageous results may be accomplished:

With reference to the drawings, 15 designates generally an armature having a shaft 16, winding 17 and a commutator 18, the same being held between the jaws 19 and 20 of a vice at the work-bench or other suitable location.

My device consists of a cylindrical barrel designated 21 which is fixed to the armature shaft, and a rotor part, designated generally 22, which may rotate about the barrel part as a bearing to carry a bit and provide a machine cut on the outer surface of the commutator.

The barrel part, designated generally 21, is shown in section in Figs. 9 and 10 and consists of cylindrical block having a central cylindrical bore 23. The bore 23 extends but partially axially through the cylindrical block, while at its other end there is a square opening 26 centrally located. A slot 27 is cut across on a cord of the cylindrical circle, as illustrated in Fig. 10, so as to intersect the opening 26 and is arranged substantially parallel to one of the diagonals of the square central opening 26. A jaw 28 is pivoted in this slot 27 by pin 29 so that if any cylindrical member, such as the armature shaft 16 and sleeve 30 which extends about the same, is placed in this square opening 26, it will engage the walls thereof as at 31, 32, which are in a V-shaped relation one to the other while the jaw 28 will engage the same as at 33 and provide a three-point contact with the cylindrical portion to bind the same centrally in the barrel member. A bolt 34 having a head 35 engaging a shoulder 36 in the recess 37 threadingly engages the jaw 28 as at 38 so as to draw the jaw into locking position. Various sleeves 30 are provided for accommodating armature shafts of different diameters.

The rotor part of the device, designated generally 22, consists of a casting providing a cylindrical body 40 with a cylindrical bore 41 and a top or head projection 42 and a downwardly extending leg 43. This leg is split as at 44. An abutment screw 46 is threaded in one portion of the leg 43 and abuts the other portion of the leg and serves to hold these portions of the leg 43 apart and prevent the inherent action tending to contract the bore 41 onto the cylindrical part 21 from exerting too great a binding action thereon. A binding screw 45 is provided for drawing the split portions together. Should wear occur, however, adjustment is provided by means of these adjustments 45, 46 extending through these portions of the leg 43.

A substantially square recess 47 is milled in the head 42 in which the adjustment member,

designated generally 48, is slidably positioned. This member is provided with a V-shaped groove 49 to receive a V-shaped gib 50 located in the recess 47 and adjustable therein by means of the screws 51 extending through the side walls of the head 42. The adjustment of this gib is more or less a precision affair, and accordingly, these screws are set below the surface of the head 42 and are sealed in position by sealing wax or the like. A clamping screw 52 having a thumb handle 53 serves to move the gib 50 inwardly to bind the member 48 in a fixed position in the head.

An arm designated generally 54 (see Figs. 1 and 11) is provided with an ear 55 which is rockably mounted by means of its bearing opening 56 upon the stud 57 formed by reducing to cylindrical formation one end of the member 48. This ear fits against the abutment 58 formed by this reduction, while the pin 60 extends into the slot 61 in this manner to limit the movement of the arm rockably about this stud. The arm has an arcuate portion 62 which reaches within the threaded bushing 24 so that threads 63 on it may mesh with the thread 25 on this bushing. The arm is held in positions of adjustment in or out of engagement by a hand nut 64 engaging thread 65 on the end of the stud 57. The spring washer 66 serves to lock this nut in binding positions by acting through a washer 67 between it and the ear 55.

At the opposite end of the adjustment member 48 I have provided a bit carrier 69 which fits within the recess 70 in the member 48. This bit carrier is recessed as at 71 and slotted as at 71', while there is a lateral slot 72 in the opposite side of the carrier. A bit 74 fits within the recess 71 and is bound therein by the screw 75 having handle 76. The shank of this screw extends through the hole 77 in one side of the carrier and is in threaded engagement as at 78 with the other side of the carrier while extending through slot 80 in the member. The hub 79 of this handle engages the outer surface of the member 48 and draws the carrier into the recess 70 into binding position.

For vertical adjustment I provide a screw 81 having a flange 83 to extend into slot 72 in the bit carrier, the screw 81 being threaded into the member 48 which is recessed as at 84 to receive the flange 83 for greater range of adjustment of the bit carrier. By turning the handle 85, the bit carrier may be adjusted to its desired position with the screw 75 partially set up to bind the bit 74 in position; and after the correct height is acquired, a further binding of the bit in its carrier may be had by reason of further turning of the handle 76. The slot 71' enables a proper binding of the bit 74 in position, while, when released, the inherent resiliency in the carrier opens to permit release of the bit for removal of the same.

In order to rotate the part 22 about the part 21, I have provided an arm 95 extending upwardly at any convenient angle from the part 22 sufficient to provide the desired leverage for turning. Upon the upper edge of this arm a pin 96 is mounted and upon the pin there is a handle 97 which may rotate with reference to the pin.

For undercutting I provide a U-shaped carrier 87 having a leg 88 of a size to fit within the recess 71 from which the bit 74 is removed, the same being bound in position by the screw 75 and handle 76 in the same manner that the bit was bound in position. This carrier has mounted in its leg 89 a rotary cutter 90 operated by a crank

91 and handle 92, while there is a handle 93 positioned on the member 81 for moving the member 48 forward during an undercutting operation.

In some cases instead of the cylindrical barrel being internally threaded, I may form the barrel as illustrated in Fig. 14, the same being shown at 100 and provided with external threads 101. In this case the rotor member 102 is provided with an adjustable member 103; on the lower surface thereof threads are provided at 104. Movement of this member is permitted toward and from the threads 101. The member 103 is normally urged radially outwardly from the threads by a shoe 105 and leaf spring 106, the member being shown operative to and from threaded engagement by cams 107 engaging the ends of the studs 108 and 109 and operated by handle 110 to force the member through the bronze plate 111 to and from threaded engagement; the same tool adjustment of fit is provided in this member as heretofore provided in the other modified arrangement.

In operation, the armature, designated generally 15, is removed from the generator or motor and placed in a vice as illustrated in Fig. 1. The barrel part 21 of the device is clamped upon the armature shaft 16 so as to remain in fixed relation thereto. The adjustment member 48 is adjusted so that bit 74 will commence at the edge of the armature commutator for cutting the same and is properly adjusted as to height. Thereafter, the arm 54 is swung into engagement with the threads 25 and is clamped into position by the hand nut 64. Then by grasping the handle 97 and turning the member 22, the member is rotated about the barrel and is fed forward by the screw 25 so that the tool will cut the commutator to true-up the same.

This cutting action usually causes the mica or other insulation between the sections of the commutator to be at the same surface as the commutator section, and this insulation must be undercut. For this undercutting I remove the armature from the vice and clamp the leg 43 of the device in the vice; then I remove the bit 74 and replace it with the carriage 81, adjusting the same to cause the tool 90 to take the proper depth cut by reason of the handle 85. Nut 64 is loosened and the arm 54 is thrown out of engagement with the thread, while the binding screw 53 is loosened so as to permit movement of the member 48 with reference to the head. The member 22 is held in fixed relation in a vice or other suitable support while the member 48 is fed forwardly by its handle 93, while at the same time the cutter 90 is rotated through the crank 91 and handle 92. After one cut is performed, while the leg 43 of the device is held in the vice, the armature is turned until the next insulation is presented to the cutter and the operation then repeated.

In this manner each undercutting may be performed by utilization of substantially the same device as performed the function of trimming the commutator of the armature.

The foregoing description is directed solely towards the construction illustrated, but I desire it to be understood that I reserve the privilege of resorting to all the mechanical changes to which the device is susceptible.

I claim:

1. In an armature commutator device, two relatively rotative parts, means for binding one part on the armature shaft, comprising an opening in

the part with two flat surfaces in a V-shaped relation forming the wall of the opening, said bound part having at one section an outer surface forming a part of a cylinder, a jaw at said section within the completion of the cylinder to force a shaft to be bound against said flat surfaces, a cutting tool carried by the other part, threads provided on one of said parts, and means on the other part for releasably engaging said threads for axially moving said parts upon relative rotation thereof.

2. In an armature commutator device, a cylindrical barrel part having an opening therein with two flat surfaces forming the wall of the opening and having a V-shaped relation one to the other, said barrel having at one section an outer surface forming a part of a cylinder, a jaw at said section within the completion of said cylindrical outer surface to force a shaft to be bound against said flat surfaces and bind the barrel part thereon, a rotary part revolvably and slidably mounted on the outer cylindrical surface of the barrel part, and disengageable threaded means on said parts for relatively axially moving the parts when relatively rotated with said means engaged.

3. In an armature commutator device, a cylindrical barrel part provided with means to clamp an armature shaft therein, said barrel part being provided with a bore and internal threads, a rotary part revolvably and slidably mounted on the outer cylindrical surface of the barrel part and carrying a tool, an arm located in said bore and swingably mounted on the rotary part to threadingly engage said internal threads to feed the tool when the parts are relatively rotated, means to clamp said arm in either engaged or disengaged position with said threads, and a handle mounted on said rotary part to revolve the same about said barrel for actuating said tool.

4. In an armature commutator device, two relatively rotative and slidable parts, means for binding one part on the armature shaft, a cutting tool carried by the other part, one of the parts being provided with a central threaded bore and an arm pivoted on the other part on an axis located at a point spaced from the axis of said bore and provided with threads engaging the threads of the bore for relatively axially moving said parts upon relative rotation thereof, said arm being movable about said pivot to cause engagement or disengagement of said threads.

5. In an armature commutator device, a cylindrical barrel part provided with a V-shaped opening, a clamping jaw to clamp an armature shaft in said opening to hold the same firmly therein, said barrel part being provided with a bore and internal threads, a rotary part revolvably and slidably mounted on the outer cylindrical surface of the barrel part, a member axially slidably mounted in said rotary part, a tool holder carried by said member at one end, threaded means to adjust said tool holder in a straight line toward and from the axial center of said barrel part, an arm swingably mounted on the other end of said member to extend into said barrel and threadingly engage said internal threads, means to clamp said arm in either engaged or disengaged position with said threads, and a handle mounted on said rotary part to revolve the same about said barrel for actuating said tool.

ERVIN BOWKER.

CERTIFICATE OF CORRECTION.

Patent No. 2,308,671.

January 19, 1943.

ERVIN BOWKER.

It is hereby certified that error appears in the above numbered patent requiring correction as follows: In the grant, lines 3 and 14, and in the heading to the printed specification, name of assignee, for "Major W. Wheelock" read --Major W. Wheelock--, as shown by the record of assignments in this office; and that the said Letters Patent should be read with this correction therein that the same may conform to the record of the case in the Patent Office.

Signed and sealed this 9th day of March, A. D. 1943.

Henry Van Arsdale,
